C. C. ABBOTT

ELECTRIC HEATING UNIT

Original Filed Feb. 8 1922

Inventor:
Charles C. Abbott
by *Albert Davis*
His Attorney

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

ELECTRIC HEATING UNIT.

Application filed February 8, 1922, Serial No. 534,924. Renewed February 12, 1924.

To all whom it may concern:

Be it known that I, CHARLES C. ABBOTT, a citizen of the United States, residing at Pittsfield, in the county of Berkshire, State 5 of Massachusetts, have invented certain new and useful Improvements in Electric Heating Units, of which the following is a specification.

My invention relates to electric heating 10 units and has for its object improvements in "sheath wire" heating units.

More specifically my invention relates to electric heating units of the "sheath wire" type in which a resistance element is embedded in a compacted mass of insulating 15 material enclosed by a metallic sheath, such, for example, as described and claimed in my Patent No. 1,367,341, dated February 1, 1921. I have found that when making 20 sheath wire heating units of relatively great length, necessitating the use of long tubes, it is difficult to keep the resistance element in a central position in the metallic sheath. This is due to two causes; first, due to the 25 difficulty in holding a long resistance element centrally of the sheath while filling the sheath with powdered insulating material; and second, due to the fact that in the swaging operation the insulating material 30 tends to flow and pile up ahead of the swaging machine dies in such manner as to force the resistance element from its central position into contact with the sheath, grounding the unit.

In accordance with my present invention 35 I have provided insulating supports placed at intervals along the length of the resistance conductor for positively holding it centrally of the metallic sheath. I have also 40 provided a simple and reliable connection between the terminal and the resistance conductor whereby the unit may be reduced in diameter to any desired extent without injury to either the resistance conductor or the 45 terminal. In carrying out this part of my invention I have provided a recess in the terminal into which the end of the sinuous resistance element is forced, the end of the terminal then being bent or pinched on the 50 resistance element to retain it in place.

For a more complete understanding of 55 my invention reference should be had to the accompanying drawing in which Fig. 1 is a section view showing an electric heating unit constructed in accordance with my in-

vention before the swaging operation; Fig. 2 is an end elevation view of Fig. 1; while Fig. 3 is a view partly in section showing the completed unit.

Referring to the drawing, in one form of 60 my invention the elongated heating unit 10 comprises a sinuous or helical resistance element 11 extending centrally of a metallic sheath 12. The resistance element is made of a suitable high resistance material having 65 considerable resiliency, such as nickel-chromium alloy. Spacing or supporting insulators 13 are provided at intervals on the resistance element for positively holding it centrally of the sheath. The supporting insulators consist of washers 14 of insulating 70 material, such as mica, mounted on metallic eyelets 15. They are slipped on the resistance element and spaced along its length as desired, the eyelets being then compressed 75 or bent on the resistance element to hold the supporting insulators in place.

Metallic terminals 16 and 17 are provided for the resistance element. Each terminal is formed with a longitudinal recess 18 into 80 which the resistance element is forced for a short distance so as to enclose a plurality of turns, the end of the terminal then being bent or pinched over on the resistance element to secure it in place. The recess 18 85 is slightly smaller than the resistance element which is contracted somewhat by twisting, turning or screwing it with relation to the terminals when it is forced into the recess. When released, the resistance element 90 uncoils against the inner surface of the recess, making a good electrical contact therewith, this contact being maintained by the resiliency of the resistance element.

In assembling the heating unit as shown 95 in Fig. 1, the resistance element with the spacing insulators and the terminals attached, as shown in the drawing, is inserted in the metallic sheath 12. The sheath is closed at one end, for example, at the right-hand end, by a solid washer 19 which fits on terminal 17, holding the terminal centrally 100 of the sheath, the sheath being countersunk to receive the washer. A clip 20 is then slipped on terminal 17 and seated in a shallow groove in the terminal so as to hold the terminal against longitudinal movement under the tension of the resistance element. The resistance element is next stretched to 105 separate its turns and terminal 16 secured in 110

a similar manner centrally of the sheath and against longitudinal movement under the tension of the resistance element by a star washer 21 and a clip 22. Sufficient tension 5 is applied to the terminals by the resistance element to hold the washers to their seats.

The sheath is now filled through the openings in the star washer with a powdered heat refractory insulating material 23, such 10 as magnesium oxide. To accomplish this the sheath is held in an upright position in a special vibrating machine (not shown) with the end provided with the star washer uppermost. As the sheath is filled with the 15 insulating material through the openings in the star washer, it is vibrated to shake the insulating material together and distribute it uniformly around the terminals, the resistance element, and the supporting insula- 20 tors 13. The supporting insulators fit loosely in the sheath so that the insulating material is free to pass around them, as well between the turns of the resistance element and through the centers of the supporting 25 members. When the sheath has been filled, a solid washer 24 is inserted in place around terminal 16 to close the tube. Both ends of the sheath are now pinched or bent at intervals 30 25, as shown in Fig. 2, so as to secure the washers in place.

The entire unit is now passed through a swaging or rolling machine for the purpose 35 of compacting the insulating material within the sheath to a hard dense mass, the swag- 40 ing operation reducing the diameter and in- creasing the length of the unit. It will be observed that during the swaging operation the insulating material will be prevented from piling up or flowing ahead of the 45 swaging machine die by the supporting insulators 13, and consequently the resistance element will be firmly embedded in the com- pacted insulating material in a central position 50 in the sheath. The terminals 16 and 17 are gradually reduced in diameter by the 55 swaging, the recessed ends contracting around the resistance element.

In case it is necessary to reduce the diameter 55 of the unit considerably in order to obtain the desired length or for any other reason, it may be desirable to pass the unit through the swaging machine a number of times so as to reduce its diameter gradually. In this event the unit may be annealed be- 60 tween the successive swaging operations. By means of my invention I have been en- abled to construct heating units of any de- sired length and to reduce their diameter by swaging, for example, from $\frac{5}{8}$ " before swag- 65 ing to $\frac{1}{2}$ " after swaging, the unit being an- nealed several times during the course of this reduction. After the unit has been swaged to the desired extent, the washers at each end and the clips are cut off or otherwise removed and the ends of the unit

squared off, as shown in Fig. 3. The terminals are held firmly in place by the compacted insulating material in which they are embedded.

While I have described my invention as 70 embodied in concrete form and as operating in a specific manner in accordance with the provisions of the patent statutes, it should be understood that I do not limit my invention thereto, since various modifications 75 thereof will suggest themselves to those skilled in the art without departing from the spirit of my invention, the scope of which is set forth in the annexed claims.

What I claim as new and desire to secure 80 by Letters Patent of the United States, is:—

1. An electric heating unit comprising an elongated sheath, a resistance element ex- 85 tends lengthwise in said sheath, insulating supports for said resistance element spaced along the length thereof, and powdered in- 90 sulating material within said sheath com- pacted around said resistance element.

2. An electric heating unit comprising an elongated sheath, a sinuous resistance element 95 extending lengthwise in said sheath, insulating supports for said resistance element se- cured at intervals along the length thereof, and powdered heat refractory insulating material within said sheath compacted to 100 a hard dense mass around said resistance element.

3. An electric heating unit comprising an elongated sheath, a helical resistance ele- 105 ment extending lengthwise in said sheath, insulating supports for said resistance ele- 110 ment secured at intervals along the length thereof, terminals recessed to fit tightly over the ends of said resistance element, and powdered heat refractory insulating ma- 115 terial within said sheath compacted to a hard dense mass around said terminals and said resistance element.

4. The method of forming an electric heating unit which consists in mounting a 110 resistance element centrally of a metallic sheath on insulating supports spaced at in- 115 tervals along the length thereof, filling the sheath with powdered insulating material and then compacting the insulating material around the resistance element.

5. The method of forming an electric heating unit which consists in securing in- 120 sulating supports along the length of a sinuous resistance element, inserting the same in a metallic sheath, filling the sheath with powdered heat refractory insulating material, and then compacting the insulating material to a hard dense mass around the resistance conductor by reducing the 125 sheath.

6. The method of forming an electric heating unit which consists in securing in- 130 sulating supports along the length of a helical resistance element, securing terminals to

the resistance element, inserting the same in a metallic sheath, filling the sheath with powdered heat refractory insulating material, and then compacting said insulating material to a hard dense mass around the terminals and resistance element by reducing the sheath.

7. An electric heating unit comprising an elongated sheath, a sinuous resistance element extending lengthwise of said sheath, a terminal for said resistance element provided with a recess into which the resistance element is forced so as to be maintained in electrically conducting relation with said terminal by virtue of its own resiliency, and powdered insulating material within said sheath compacted around said resistance element and said terminals.

8. An electric heating unit comprising an elongated sheath, a helical resistance element extending lengthwise of said sheath, a terminal for said resistance element provided with a longitudinal recess adapted to receive a plurality of turns of the conductor and having its end bent over to secure the conductor in place, and powdered heat refractory insulating material within said sheath compacted to a hard dense mass around said resistance element and said terminal.

9. An electric heating unit comprising an elongated sheath, a helical resistance element extending lengthwise in said sheath, terminals for said resistance element each provided with a recess into which a plurality of turns of said resistance element are forced so that said resistance element is maintained in electrically conducting relation with said terminal by virtue of its own resiliency, said terminals having their edges bent over to secure the resistance element in place, and powdered heat refractory insulating material within said sheath compacted to a hard dense mass around said resistance element and said terminals. 45

10. The method of forming an electric heating unit which consists in connecting terminals to a helical resistance element by forcing the resistance element into recesses in said terminals by twisting the resistance element to contract it, bending the ends of said terminals over to secure the resistance element in place, inserting the whole in a metallic sheath, filling the sheath with powdered insulating material, and then compacting the insulating material around the resistance element and the terminals. 55

In witness whereof, I have hereunto set my hand this second day of February, 1922.
CHARLES C. ABBOTT.
